United States Patent

Des. 240,314
Patented June 22, 1976

240,314

CAN

Walter K. Chlystun, 327 St. James Drive,
Spartanburg, S.C. 29301

Filed Dec. 3, 1973, Ser. No. 420,869

Term of patent 14 years

Int. Cl. D9—03

U.S. Cl. D9—218

FIG. 1

FIG. 2

FIG. 3

FIG. 1 is an elevational view of a can showing my new design;

FIG. 2 is an elevational view looking from the right of FIG. 1; and

FIG. 3 is a top plan view thereof.

I claim:

The ornamental design of a can, substantially as shown and described.
